UNITED STATES PATENT OFFICE

2,458,869

RECIPROCATING PUMP OR MOTOR

Joshua Challiner Naylor, Monkseaton, England,
assignor to Vickers-Armstrongs Limited, London, England, a company of Great Britain

Application January 4, 1945, Serial No. 571,249
In Great Britain October 27, 1943

Section 1, Public Law 690, August 8, 1946
Patent expires October 27, 1963

10 Claims. (Cl. 74—51)

1

This invention relates to reciprocating pumps or motors of the fixed or variable stroke radial type in which cylinders are disposed in a housing about a shaft carrying an eccentric, the pistons reciprocating in the cylinders and being in driving connection with the eccentric. For example the invention is concerned with pumps which include a series of radially arranged cylinders each containing an associated piston, the flow of fluid to and from the cylinders being controlled by a suitable valve or valves for example, the eccentrically operated valve of the self-sealing type forming the subject of prior British Patent No. 503,148. Examples of such radial pumps are described and illustrated in the specifications and drawings accompanying co-pending patent applications Nos. 505,491 and 505,490, both filed October 8, 1943, the latter having issued as Patent No. 2,426,100 on August 19, 1947.

It has been proposed in the case of radial pumps which are eccentrically operated to fit the eccentric with a surrounding annular ring, said ring being freely revoluble about the eccentric and to bifurcate or flat the inner end of each piston for the reception of a roller or rollers, the latter making rolling contact with said ring, each roller being mounted upon a pin which extends transversely through aligned borings in the pistons, all the rollers being maintained in contact with the ring during the suction or return stroke of the pistons by a retaining ring or rings disposed alongside the pistons, said retaining rings or rings surrounding the pins or rollers and contacting their outer peripheral surfaces.

It is desirable in such pumps that any tendency for the pistons to rotate about their axes during operation should be prevented and the chief object of the present invention is to obviate any such axial turning movement.

According to this invention a radial pump or motor of the type employing an eccentric to drive the piston is characterised by the combination with the pistons and the eccentric of means to prevent rotation of the pistons about their axes, said means comprising two endless abutments common to all of the pistons and engaging with co-operating abutments carried by the pistons.

One form of the invention comprises annular retaining rings which engage flats on the pistons, another form comprises a channel in the periphery of the eccentric receiving rollers on the pistons, and a still further form consists in engaging grooves in the piston pins with the inner edges of two retaining rings.

In order that the invention may be clearly

2

understood and readily carried into effect drawings are appended hereto illustrating embodiments thereof, and wherein,

Figure 1 is a fragmentary sectional view taken diametrically through one of a set of pistons in radial cylinders and showing the co-operation of retaining rings and flats on the piston for preventing rotation of the piston about its axis.

Figure 2 is a sectional side elevation through the appropriate part of the pump or motor to show the piston rotation preventing means of Figure 1.

Figure 3 is a broken diametrical sectional elevation through a pump incorporating retaining rings which engage in notches in the end parts of the piston pins projecting beyond the piston for preventing rotation of the pistons about their axes.

Figure 4 is a section on the line 4a—4a of Figure 3 but showing the pistons in full.

Figure 5 is a section similar to Figure 3 but showing an alternative manner of effecting inter-engagement between the piston pins and the retaining rings.

Figure 6 is a detail sectional elevation showing the use of a channel in the eccentric and adapted to co-operate with rollers on the pistons to prevent the said rotation of the pistons.

Figure 7 is a view similar to Figure 6 but showing a slight modification, and Figure 8 is a detail sectional elevation of another embodiment of the invention.

Referring to Figures 1 and 2 of the drawings, each piston 1 has a bifurcated inner end in the form of two symmetrical parallel limbs 2 having flat inner and outer faces parallel with a diameter of the piston and sufficiently widely spaced to receive a thick cylindrical roller 3 contacting the outer ring 4 of the eccentric 5 mounted on the pump shaft 6. Each roller has flat annular side faces making light contact with the inner flat faces of the furcations 2 and is supported by a cylindrical piston pin 7 passed through circular holes in the furcations and lightly contacting at their ends with two retaining rings 8 of L section which engage by the inner tracks of their outer cylindrical parts with the pins 7 to maintain the rollers in contact with the ring 4 during the suction or return stroke of the piston. This ring 4 is supported on the eccentric by needle bearings 9.

The chief features of the foregoing arrangement as far as the present invention is concerned is that the opposed annular faces 10 of the cylindrical outer parts of the retaining rings con-

tact with the outer flat faces of the furcations 2 whilst the outer annular faces 11 make sliding contact with fixed annular guide plates 12. It will be appreciated that with such an arrangement that the retaining rings form positive abutments preventing rotation of the pistons about their axes.

In the embodiment shown in Figures 3 and 4 each piston pin 1 is notched as at 14 at a point near each extremity, for the reception of the inner peripheral edge of the adjacent arc of a pair of retaining rings 8, the bottom of each notch 2 being of arcuate shape and radiused to correspond with the inner diameter of the appropriate ring 8, each notch being so positioned that the inner face of each retaining ring makes rubbing contact with the adjacent outer flat face of the bifurcated inner end of the appropriate piston 1. In this way the piston pins themselves prevent axial separation of the retaining rings 8 and thereby maintain the largest area of annular face of each such ring in contact with the appropriate flat furcation 2, so that axial turning movement of the pistons is prevented and furthermore the retaining rings by virtue of their notched engagement with the pins 2 serve to prevent endwise movement of the pins within their borings in the piston and so constitute a self retaining assembly. The pins support rollers 3 the annular faces of which rotate against the opposed flat faces of the furcations 2 of the inner ends of the pistons.

It is preferred that with the above arrangement each retaining ring shall be of substantially L shape in cross-section as shown, each retaining ring being so disposed that the inner face of the inwardly directed web thereof makes light rubbing contact with the adjacent face of the piston, the other or axially directed web being directed outwardly, i. e. away from the piston and acting as a stiffening web for the ring.

In the alternative arrangement shown in Figure 5 each pin 1 is cut away at each end to form a step 15 on the outer part of its peripheral surface, as distinct from being notched in such outer part as aforesaid, to form two portions which project from the piston and are reduced in thickness, the outer faces of the projecting ends of the pin being of arcuate shape and of a curvature corresponding to the inner peripheral curvature of the retaining rings 8.

The retaining rings in this modified arrangement may be of simple rectangular shape in cross-section as shown, the inner faces of the retaining rings making light rubbing contact with the adjacent flat sides of the forked inner end of the appropriate piston as hitherto and the outer faces with suitable abutments 12 in the pump casing. By cutting away the extremities of the pins to a sufficient depth, the overall diameters of the retaining rings are consequently reduced, thus reducing to a certain extent the overall diameter of the pump.

In either of the arrangements hereinbefore described the rollers 3 may make simple surface contact with the ring 4 which is free revolvably mounted upon the eccentric 5, but in an alternative arrangement (see Figure 6) the ring 4 may be formed with continuous peripheral recess 16 constituting a guideway in which the rollers can run. This guideway receives the rollers 3 for a depth adequate for preventing the pistons turning about their axes and relieving the retaining ring or rings of this function.

To afford ample latitude for changes in direc-

tion of the axes of the pistons relatively to the periphery of the eccentric it is desirable with some pumps and motors that the piston pins should be free to spin about their axes rather than to restrain such spinning by the use of the steps 15 radiused to conform with the radius of the inner edges of the retaining rings. In Figure 7 is shown an arrangement affording this spin as well as affording the minimum friction between each roller 3 and piston pin 1. The piston pin 1 is hollowed to fit smoothly upon a cylindrical centre pin 17 which projects beyond the ends of the piston pin 1 and the outer flats of the furcations 2 to make rolling contact with the inner cylindrical surfaces of the opposed axially projecting parts of the retaining rings 8 which by their opposed annular faces 18 locate the pin 17 against axial displacement whilst having a clearance 19 between their opposed annular edges and the outer flats of the furcations 2. Turning of the piston 1 about its axis is prevented, in the same manner as in Figure 6, i. e. by the roller 3 running in a circumferential channel 16 in the eccentric ring 4.

Instead of a bifurcated inner end to each piston a single central or diametrical lug 20 can be provided as shown in Figure 8, the piston pin 1 carrying a pair of rollers 3 running in two circumferential channels 16 (or a single wide channel) in the eccentric ring 4 to prevent rotation of the piston about its axis. The rollers 3 can engage and traverse the inner tracks of the two retaining rings which have their axially directed cylindrical peripheries interposed between the rollers and the steps 21 formed in the peripheries of the pistons when milling the lugs 20.

The use of the pins 17, or of the pairs of rollers 3, engaging the inner tracks of the retaining rings as shown in Figures 7 and 8 considerably minimises friction and leaves the retaining rings free to precess without imposing drag on the piston pins in directions transverse to the piston axes and keeps the axes of the piston pins 1 truly squared in relation to the plane parallel with all of the piston axes.

It will be appreciated that the retaining rings where they engage the flats on the pistons or the grooves in the piston pins, and the channels 16 where they engage the flats or annular faces of the rollers constitute two endless annular abutments engaging with co-operating abutments carried by the pistons to prevent rotation of the pistons about their axes.

I claim:

1. In a pump or motor of the radial type an eccentric, cylinders substantially radiating from the eccentric, pistons reciprocating in the cylinders, rollers carried by the pistons and engaging the periphery of the eccentric and means restraining the pistons from turning about their axes, said means comprising diametrically opposed flats on the pistons and a pair of axially spaced annular retaining rings engaging the flats on the pistons, headless cylindrical piston pins passed diametrically through the pistons and forming axles for the rollers, and integral abutment surfaces on the piston pins engaging the retaining rings at annular surfaces opposed to the piston for holding the piston pins against axial displacement.

2. In a pump or motor of the radial type an eccentric, cylinders substantially radiating from the eccentric, pistons reciprocating in the cylinders, rollers carried by the pistons and engaging the periphery of the eccentric and means re-

straining the pistons from turning about their axes, said means comprising diametrically opposed flats on the pistons and a pair of axially spaced annular retaining rings engaging the flats on the pistons, headless cylindrical piston pins passed diametrically through the pistons and forming axles for the rollers, and integral abutment surfaces on the piston pins engaging the retaining rings at annular surfaces opposed to the piston for holding the piston pins against axial displacement, said abutment surfaces on the piston pins comprising plane ends perpendicular to the axes of the piston pins abutting against opposed annular surfaces of the retaining rings, opposed inwardly directed peripheral flanges integral with said retaining rings abutting against said flats on the piston.

3. In a pump or motor of the radial type an eccentric, cylinder, cylinders substantially radiating from the eccentric, pistons reciprocating in the cylinders, rollers carried by the pistons and engaging the periphery of the eccentric and means restraining the pistons from turning about their axes, said means comprising diametrically opposed flats on the pistons and a pair of axially spaced annular retaining rings engaging the flats on the pistons, headless cylindrical piston pins passed diametrically through the pistons and forming axles for the rollers, and integral abutment surfaces on the piston pins engaging the retaining rings at annular surfaces opposed to the pistons for holding the piston pins against axial displacement, said abutment surfaces on the piston pins comprising steps formed in the ends of the piston pins and offering to the opposed surfaces of the retaining rings plane surfaces co-planar with the flats on the pistons.

4. In a pump or motor of the radial type an eccentric, cylinders substantially radiating from the eccentric, pistons reciprocating in the cylinders, rollers carried by the pistons and engaging the periphery of the eccentric and means restraining the pistons from turning about their axes, said means comprising diametrically opposed flats on the pistons and a pair of axially spaced annular retaining rings engaging the flats on the pistons, headless cylindrical piston pins passed diametrically through the pistons and forming axles for the rollers, and integral abutment surfaces on the piston pins engaging the retaining rings at annular surfaces opposed to the piston for holding the piston pins against axial displacement, said abutment surfaces comprising grooves in the peripheries of the pins formed between their ends and the flats on the pistons and engaged by the retaining rings.

5. In a radial pump or motor a set of radial cylinders, pistons reciprocating in said cylinders, an eccentric, rollers carried by the pistons and tracking against the periphery of the eccentric, a pair of diametrically opposed flats on each piston, two axially spaced annular retaining rings contacting with all of said flats, forked ends with said pistons between the furcations of which are located the said rollers, said flats comprising the outer surfaces of the furcations, headless piston pins passing through said furcations and comprising the axles of the rollers, opposed inwardly directed cylindrical flanges with said rings engaging by their free ends against said flats and overhanging the ends of the piston pins, and plane surfaces on the ends of the piston pins perpendicular to the axes of the pins and engaging opposed annular surfaces of the retaining rings.

6. In a radial pump or motor a set of radial

cylinders, pistons reciprocating in said cylinders, an eccentric, rollers carried by the pistons and tracking against the periphery of the eccentric, a pair of diametrically opposed flats on each piston, two axially spaced annular retaining rings contacting with all of said flats, forked ends with said pistons between the furcations of which are located the said rollers, said flats comprising the outer surfaces of the furcations, headless piston pins passing through said furcations and comprising the axles of the rollers, steps formed at the ends of the piston pins by removing parts of the peripheries of such pins and engaging by their axially directed surfaces with internal cylindrical surfaces of the retaining rings, said axially directed surfaces of the pins being radiused to correspond with the radius of such internal surface of the retaining rings, and the inner ends of such steps being co-planar with and abutting against the opposed annular surfaces of the retaining rings.

7. In a radial pump or motor an eccentric, a set of cylinders disposed circumambiently about the eccentric, pistons reciprocating in the cylinders, forks on the ends of the pistons opposed to the eccentric, piston pins passing through such forked ends, rollers in such forked ends rotating on the pins, an endless channel in the periphery of the eccentric in which the rollers track, the opposed annular side walls of the channel engaging the sides of the rollers to prevent rotation of the pistons about their axes, and a pair of retaining rings surrounding and contacting the ends of the piston pins.

8. In a radial pump or motor an eccentric, a set of cylinders disposed circumambiently about the eccentric, pistons reciprocating in the cylinders, forks on the ends of the pistons opposed to the eccentric, piston pins passing through such forked ends, rollers in such forked ends rotating on the pins, an endless channel in the periphery of the eccentric in which the rollers track, the opposed annular side walls of the channel engaging the sides of the rollers to prevent rotation of the pistons about their axes, each piston pin being constituted by a hollow cylindrical outer member fixed in the piston and a centre pin free to rotate in said hollow member and engaged at its ends with retaining rings.

9. In a radial pump or motor an eccentric, a set of cylinders disposed circumambiently about the eccentric, and pistons reciprocating in the cylinders, rollers carried by the ends of the pistons opposed to the eccentric, an endless channel in the periphery of the eccentric in which the rollers track, the opposed annular side walls of the channel engaging the sides of the rollers to prevent rotation of the pistons about their axes, piston pins passed diametrically through the pistons and forming the axles of the rollers, and a pair of retaining rings, the ends of the piston pins having parts of their peripheries removed to form steps seating in the retaining rings.

10. In a radial pump or motor an eccentric, a set of cylinders disposed circumambiently about the eccentric, and pistons reciprocating in the cylinders, a pair of co-axial rollers carried by the end of each piston opposed to the eccentric, and endless channelling in the periphery of the eccentric in which the pairs of rollers track, opposed annular side walls of the channelling forming abutments for sides of the rollers to prevent rotation of the pistons about their axes, piston pins passed diametrically through the pistons and each forming the axle for a pair of rollers carried

by a piston, and a pair of retaining rings with opposed inwardly directed peripheral parts overhanging the peripheries of the rollers, and the circumferences of the pistons each being cut away to a lug formation at the inner end to accommodate the rollers and the said inwardly directed peripheral parts of the retaining rings.
